EXPLOSION ENGINE EXHAUST MUFFLER

John R. Russo, Marlborough, Mass.

Application June 3, 1954, Serial No. 30,790

Term of patent 14 years

(Cl. D14—6)

FIG.1.

FIG.2.

To all whom it may concern:

Be it known that I, John R. Russo, a citizen of the United States and resident of Marlborough, county of Middlesex, and Commonwealth of Massachusetts, have invented a new, original, and ornamental Design for an Explosion Engine Exhaust Muffler, of which the following is a specification, reference being had to the accompanying drawing, forming part thereof.

Fig. 1 is a perspective view of an explosion engine exhaust muffler embodying my new design; and

Fig. 2 is a side elevational view of the same.

I claim:

The ornamental design for an explosion engine exhaust muffler, substantially as shown.
